UNITED STATES PATENT OFFICE

2,417,379

BRAKE FOR LOOM LETOFF MECHANISM

Andrew B. Shelton, Columbus, Ga., assignor to
 A. B. Shelton Corporation, a corporation of
 Georgia

Application February 12, 1945, Serial No. 577,433

1 Claim. (Cl. 139—108)

1

This invention relates to let-off mechanisms for looms.

In let-off constructions at present in use the ratchet which progressively rotates the warp beam is restrained from free rotation by means of a friction clamp which encircles a friction hub or drum, and the latter is fixed to the ratchet between the ratchet and a spur gear with a rock arm outside of the spur gear so that when the friction clamp must be replaced it is necessary to remove the spur gear and the rock arm. It is, therefore, an object of this invention to provide an improved friction clamp or brake which may be removed without removal of adjacent parts so that the renewal of the friction lining can be accomplished with a minimum of lost time.

Another object of this invention is to provide a brake for loom let-off mechanism which is formed at its lower end with an open fork engaging with the rock shaft correlated with the yarn mass on the warp beam so that the arm may be quickly disengaged from the rock shaft without disconnecting other parts associated with the rock shaft, or other elements carried by the pinion shaft which drives the warp beam gear.

A further object of this invention is to provide a device of this kind which is simple in construction and which may be incorporated with the present construction of looms without change in the present parts, and will reduce the stoppage time of the loom for replacement of the friction lining to a minimum.

In the drawings:

Figure 1 is a detail side elevation of a device constructed according to an embodiment of this invention mounted on the related portions of the loom which are shown in section and partly broken away.

Figure 2 is a fragmentary top plan of the device.

Referring to the drawings 10 designates a pinion shaft for a loom and on which are mounted the usual ratchet and gearing as disclosed more fully in Patent Number 647,815, dated April 17, 1900.

The warp beam is adapted to be progressively rotated and the amount of rotation is controlled by rocking movement of a lever or arm 11 the upper end of which engages the yarn mass on the warp beam as shown in Patent No. 647,815. The shaft 10 has loosely mounted thereon a ratchet fragmentarily shown at 10' and fixedly secured to said ratchet is a brake drum 12 which is concentric of the shaft 10 and this drum is encircled by means of a friction clamp or brake band, gen-

2

erally designated as 14. The brake band 14 includes a substantially semi-circular band member 13 which is formed integrally with an elongated arm 15. The band 14 also includes a second arcuate member 16 which is pivotally mounted at one end between a pair of ears 17, carried by the lower end of the member 13. The arcuate member 16 is formed with a reduced thickness hinge lug 18a engaging between the ears 17 and mounted on a pivot pin 17a which extends between the ears 17. The hinge construction is such that the arcuate member 16 may be swung substantially 180° from an operative to an inoperative position. The band member 13 has extending from the free end thereof, a lug 18 which is formed with an opening 19 through which a band tensioning bolt 20 loosely engages. The bolt 20 also loosely engages through an opening 21 which is formed in a lug 22 carried by the free end of movable band member 16.

A band clamping lever 23 is pivotally mounted as at 24 on the bolt 20, being formed with a cam 25 engaging against the adjacent face of lug 22. Bolt 20 is threaded at its opposite end, as indicated at 26, and a nut 27 is threaded on the threads 26 and bears against a band tensioning spring 28 which is positioned about the bolt 20 between the nut 27 and lug 18.

The lever 23 is formed with an outwardly extending handle 29 and the lever 23 together with the bolt 20, is held against rotation by means of spaced ears 30 and 31 carried by the movable band 16 and engaging on opposite sides of lever 23. A friction band 32 is secured to the inner or concave side of the band member 13, and extends outwardly, as indicated at 33, on the inner side of lug 18. Bolt 20 loosely engages through the extended band portion 33. A second brake band 34 is secured to the inner side of the band member 16, and these two bands or linings 32 and 34 are adapted to normally engage the brake drum 12, so that ratchet 10' is held against free rotation.

The lower end of arm 15 is forked or of U-shape being provided with spaced arms 35 and 36 engaging on opposite sides of the rock shaft 37 which is carried by the operating member 11.

As shown in Patent 647,815, the normal position of the brake band arm 15 is on the inner side of a second arm, and there are gears on shaft 10 outwardly of these two arms.

With prior constructions it has been necessary to remove said outer arm in order to reline the brake band and to remove such arm it has also been necessary to remove the related gears.

However, with a let-off mechanism brake construction as hereinbefore described, the brake band may be opened as shown in dotted lines in Figure 1, bolt 20 being unthreaded from nut 21 and then the opened assembly may be swung to the right and lifted from rockshaft 31. In the open position of the assembly the brake will be disposed wholly on one side of the dot and dash center line of shaft 10, as shown in Figure 1, so that the assembly can then be removed from the loom without disconnecting any other part of the loom. The brake lining may then be applied to the inner sides of the brake band members and the lever construction reassembled.

It will, therefore, be apparent that to renew 15 the brake lining, which must be renewed rather frequently, no additional parts need be removed from the loom. This provides, therefore, for eliminating a considerable loss of time which has heretofore been necessary in relining these brakes.

I claim:

In a loom warp beam let-off mechanism of the type having a beam gear, a pinion shaft, a ratchet loosely mounted on said pinion shaft and a rock-shaft: a brake including a brake drum fixed to said ratchet; a brake band surrounding said brake drum and comprising a first band member, 30 a second band member, means pivotally connecting said band members together at one end, means releasably connecting said band members

together at the other end; an arm fixed at one end to said first band member and being forked at the other end, said forked end embracing said rockshaft to prevent rotation of said brake band; the construction being such that when said releasable connection is released said second band member may be swung to a position wherein both band members lie wholly on one side of a straight line passing through the center of said pinion shaft whereby said brake may be removed from the loom without removing any other parts of said let-off mechanism.

ANDREW B. SHELTON.
